RADIO RECEIVING APPARATUS

Lewis M. Clement, Mountain Lakes, N. J., assignor,
by mesne assignments, to Federal Telegraph
Company, Newark, N. J., a corporation of
California

Application May 10, 1929, Serial No. 361,982

15 Claims. (Cl. 250—20)

This invention relates to broadcast receiving apparatus and particularly to a system for actuating the tuning apparatus of a radio receiver at points remote from the receiver.

5 One of the objects of this invention is to provide an apparatus for tuning a radio receiver from a distance with means for visually indicating at any particular control point, the precise position of the tuning apparatus at the radio receiver.

Another object of the invention is to provide a tuning system, the control of which is uniform, both at the receiver and at the remote points.

A further object of this invention is to provide 15 a remote tuning control system for a radio receiver, which will permit a listener to change his position of operation in order to obtain maximum comfort in listening to the reproduced sound from a loud speaker.

20 A still further object of the invention is to provide a tuning system which permits the component parts within the receiver to be arranged in their most advantageous manner.

A still further object is to provide a tuning system located at a distance from the receiver with means for controlling the volume at the distant tuning point.

25 A feature of the invention is that means are provided for indicating the frequency setting at any remote point, the energization or de-energization of the receiving apparatus, and whether the tuning apparatus may be operated at the receiver or at a remote point.

This invention is a radio receiver which may 30 be tuned from substantially any point in the home of the radio listener. Heretofore, radio remote control systems have been limited in the distance from the receiver at which the set may be tuned, by the length of a cord from the receiver to the remote control point. Such a system, of course, necessitated the use of a cord which may or may not be wound upon a spring sheave to eliminate the extra cord. In the present invention, the only cord which will be used is that leading from 35 an outlet in the wall to a remote control unit the length of which will be comparatively short. All other cables will be hidden in the walls or flooring of the building.

In this invention, the receiver may be tuned at 40 the receiver in the same manner as at a control point. This feature allows the receiver to be designed without regard to the location of its tuning control, permitting the positioning of the component parts of the receiver in their optimum position for obtaining a better receiving circuit and

a more compact unit. The control buttons and volume control knob may be located at convenient points on the cabinet.

The means employed in this invention for rotating the condensers of the receiver tuning system is an eddy current motor of any well known type, one of which is disclosed in F. A. Kolster co-pending application, Ser. No. 310,006, filed Oct. 3, 1928. By means of two switches of the carbon button type for controlling the speed and direction of rotation of the motor, tuning may be accomplished in an efficient and rapid manner.

At the control points, there may be located an indicating dial, in the form of a voltmeter graduated in broadcast frequencies or wavelengths 15 which is actuated by the voltage tapped from a potentiometer positioned on the rotating mechanism. The volume of the reproduced sound is controlled by a variable resistance in the plate circuits of certain of the vacuum tubes employed. 20

Other objects and advantages of this invention will be apparent, and the invention more fully understood by reference to the description hereinafter following and to the accompanying drawings, in which:

25 Figure 1 is a perspective view of a radio cabinet, containing a radio receiver, where one remote control unit may be used in a plurality of outlets located at various points;

Fig. 2 is a schematic circuit drawing of the 30 radio receiver of Fig. 1;

Figs. 3 and 4 are perspective and diagrammatic circuit views, respectively, of a remote control unit of the radio receiver of Figs. 1 and 2;

Fig. 5 is a diagrammatic circuit drawing of 35 a radio receiver circuit where a plurality of remote control units are employed;

Fig. 6 is a diagrammatic circuit drawing of one of the remote control units of Fig. 5.

40 Referring to the drawings, where similar elements are designated by identical numerals, and specifically to Fig. 1, a cabinet 5 of any well known type is shown housing a radio receiver which is energized from the common house lighting circuit by connection to a plug 6 through extension cord 7. The control of this radio receiver is by means of "on" and "off" buttons 9 and 10, respectively, motor control buttons 11 and 12 and a volume control knob 13, located on the side panel of the cabinet. It is to be understood, however, that these elements may be located on the rear, front or top of the cabinet, as the location depends solely on running the wires to any desired location. A red light 14 indicates that the set may be controlled at the 45 50 55

- cabinet, while a green light 15 indicates that the control is at a remote point. The indicator lights together with a frequency or wave length scale 16 on the tuning shaft or some rotatable portion of the system may be located under a glass covered window to be seen when tuning is being accomplished at the receiver. This tuning scale may also be a voltmeter used in the same manner as at the remote control points.
- 10 A cable 17 running under floors and in partitions contains the remote control wires leading to the remote points 18 shown in the form of outlet jacks which may be located in the baseboards or walls of different rooms.
- 15 Fig. 2 shows a circuit for the control of the radio receiver of Fig. 1. A represents a well known type of radio receiver which has its tuning condensers mounted on a single rotatable shaft. This receiver has three tuned radio stages 25, 20 and 27, feeding into a detector stage 28 with an indirectly heated cathode tube. The radio receiver is supplied from rectifier-power stage unit shown at B. This rectifier-amplifier unit consists of two audio frequency stages 29 and 30, 25 a power transformer 31, a rectifying tube 32, filter 33 and a potentiometer 34. A loud speaker 38 changes the electrical vibrations into sound vibrations.

The remote control portion of this invention 30 located at the receiver includes an eddy current motor 40, with its driving coils 41 and 42. The shaft of this motor is mechanically connected to the tuning condensers of the radio receiver A, the connection being diagrammatically illustrated by the broken lines. A potentiometer 44 with its adjustable contact 45, is shown mounted on the eddy current motor shaft but may be mounted on the condenser shaft. Relays 46 and 47 are also located in the cabinet 5. Relay 46 has contacts 65 to 71, respectively, while relay 47 has contacts 73 to 79, respectively, the operation of which will be explained hereinafter.

The control elements at the cabinet are the "on" and "off" buttons 9 and 10, respectively, the motor 45 control buttons 11 and 12, the volume control knob 13 and the red and green lights 14 and 15, respectively, which are mounted as described above in connection with Fig. 1. The cable 17 is shown comprising the individual wires 50 to 61, inclusive. 50 A remote control unit 85 as shown in perspective and diagrammatic views in Figs. 3 and 4, respectively, will be described in connection with Fig. 2 when the operation of the circuit is presented. This unit is shown plugged into one of 55 the outlet jacks 18 by means of a plug 86 and cable 87.

The motor control buttons or switches 11 and 12 are carbon pile resistances of any well known type which provide means for controlling the 60 speed of the motor as well as controlling its direction of rotation.

Referring specifically to Figs. 3 and 4, "on" and "off" buttons 89 and 90, respectively, red and green lights 91 and 92, motor control buttons 93 and 94, volume control knob 95 and a wave length indicating scale 96 are shown together with conductors 50 to 61, inclusive, leading to these elements.

The operation of the circuit shown in Figs. 2 70 and 4, is as follows: When it is desired to tune the receiver at the cabinet, pressing the "on" button 9 energizes the receiver from the supply wires 7 by a circuit which may be traced over conductor 100, conductor 101, "on" button 9, 75 coil of relay 46, conductor 102 and conductor 103,

Upon energization of the relay 46, its armature is placed in the position shown in the drawings, with contacts 65, 67, 68, 69, 70 and 71 made and contact 66 open. Energy is now sent to the power unit B over conductor 100 through primary winding of power transformer 31, conductor 104, contact 71, conductor 102 and conductor 103. It is to be noted that the "on" button 9 is normally open except upon pressure on the button itself, while the "off" switch is normally closed except when pressure is placed on the button control 10. The "on" button 9 may return to its open position after the coil of the relay 46 has been energized over a circuit through it, since the relay remains energized or locked up over a locking circuit including conductor 100, conductor 101, "off" button 10, conductor 60, "off" button 90 of the remote control unit, conductor 61, shown in Figs. 2 and 4, conductor 62, contact 78, contact 65, coil of the relay 46, conductor 102 and conductor 103. From this circuit it is obvious that pressing of either the "off" button 10 at the receiver, or the "off" button 90 at the remote control unit, de-energizes the relay 46 and breaks the power supply circuit, thereby de-energizing the set.

When it is desired to rotate the condenser shaft in one direction when the relay 46 is energized, pressure on the motor control button 11 completes a circuit from motor coil 41, contact 30 68, motor control button 11, "off" button 10, conductor 101, conductor 100, through the power source, conductor 103, conductor 102, contact 71 and back to the motor coil 41. To rotate the motor in the opposite direction with the control 35 at the cabinet, pressure on the button 12 completes a circuit from motor coil 42, contact 69, motor control button 12, "off" button 10, conductor 101, conductor 100, through the power source, conductor 103, conductor 102, contact 71 40 and back to the motor coil 42. Upon the amount of pressure on buttons 11 or 12 depends the resistance of these units which controls the speed of the motor 40 in the respective directions. The position of the tuning condenser may be 45 observed on the scale 16 shown in Fig. 1.

To energize the receiver from a remote point when the receiver is off, it is only necessary to press the button 89, and the relay 47 becomes energized changing the control to that particular remote point. However, while the relay 46 is actuated, which allows the receiver to be tuned at the cabinet and the control is desired at a remote point it is necessary to first press "off" button 90 de-energizing relay 46 and then press 50 "on" button 89 to energize relay 47. Red indicating light 14 at the cabinet is energized when the control is at the cabinet over a circuit beginning at the energizing secondary winding 106 over conductor 107, red light 14, contact 70 and 60 conductor 108, while red light 91 at the remote point is energized over conductor 107, conductor 59 in cable 17, red light 91, conductor 56, contact 70 and conductor 108. In other words, these lamps are connected in parallel and energized from the winding 106.

Volume control is accomplished by a series resistance in the common plate circuit of the radio frequency stages 25 and 26 over a circuit starting at these stages and continuing over conductor 110, control rheostat 13, contact 67, conductor 111, potentiometer 34, rectifier 32, potentiometer 34 and to the filament of the tubes at stages 25 and 26.

When it is desired to change the control point 75

from the cabinet to remote point 85, button 90 is pressed de-energizing relay 46, breaking contacts 65, 67, 68, 69, 70 and 71, and making contact 66. Pressing button 89 then energizes relay 47 over a circuit including conductor 100, conductor 101, "off" button 10, conductor 60, "on" button 89, conductor 50, winding of relay 47, conductor 102 and conductor 103 which makes contacts 73, 74, 75, 76, 77 and 79 and breaks contact 78. Relay 47 is locked up after its respective contacts are made or broken over a circuit including conductors 100, 101 and 60, remote control "off" button 90, conductors 61 and 62, contacts 66 and 79, winding of relay 47 and conductors 102 and 103.

Tuning of the set may now be accomplished at a remote point, in the same manner as at the receiver cabinet. The green light 15 at the cabinet, indicating that the control is at a remote point, has a circuit over secondary winding 106, conductor 107, green light 15, contact 74 and conductor 108. Green light 92, over a circuit employing conductors 107, 59, 55 and 108, is energized at the remote point 85. Volume control is accomplished over the remote control conductors 51 and 58, while the position of the tuning condensers is registered over a circuit including remote control conductors 54 and 57. When it is desired to rotate the tuning condensers in one direction, the motor coil 41 is energized over a circuit extending from the coil 41 over contact 76, conductor 52, remote motor control button 93, remote "off" button 90, conductor 60, "off" button 10, conductors 101, and 100, power source, conductors 103 and 102, contact 73 and to the coil 41, while the circuit for coil 42 extends from the coil over contact 75, conductor 53, remote motor control button 94, remote "off" button 90, conductor 60 "off" button 10, conductors 101 and 100, power source, conductors 103 and 102, contact 73 and to coil 42.

From the above traced circuits, it is to be noted that a very flexible method of control of the radio receiver at the cabinet or at any remote point is obtained. The pressing of an "off" button and the subsequent pressing of the "on" button, switches the control from one point to any other point at which it is desired to tune the receiver. Only one remote control unit 85 is required, this unit being taken to the listener's point of reception and plugged into the outlet jack nearest to him. The cable 87 permits considerable change in the listener's position in the neighborhood of the outlet jack being used. All the circuits are in parallel with the exception of the circuit which permits the control to be transferred from one point to another. This circuit is maintained at all times by closing circuit springs in the outlet boxes 18.

The circuits of Figs. 5 and 6 are substantially identical with those of Figs. 2 and 4. However, as a control unit is provided at each remote point, it is unnecessary, of course, to show at what point the control is as the receiver may be controlled from any position at any time. Therefore, only one light 91, which may give a red indication, is employed to show whether the set is energized or de-energized. Also the use of multiple control units simplifies the relay and circuits which will be explained hereinafter. The radio set and power supply unit of Fig. 2 is represented by the blocks A and B in Fig. 5.

To energize the radio receiver, the "on" button 9 at the cabinet, or any one of the remote control "on" buttons 89 at the remote control

points may be pressed. This action actuates the relay and connects the power source to the set. For "on" button 9, the circuit is over conductor 100, conductor 101, "on" switch 9, winding of relay 114, conductor 102 and back to the power supply. When the relay 114 is energized it makes contacts 115 and 116. Through a circuit over conductor 100, conductor 101, "off" button 10, in series through the other "off" buttons 90 at the remote points, through the contact 115 winding 10 of the relay 114, conductor 102, and the energy supply, the relay 114 is locked up. Since this circuit is in series through all of the "off" buttons, it is obvious that the circuit may be broken, and the receiver made inoperative from any remote point or at the cabinet. The volume control circuit is also a series circuit through rheostats 13 and 95 permitting the control of volume to be effected over the conductors 110 and 111 at any of the tuning locations.

The energizing circuit for the rectifying unit is over conductor 102, contact 116, conductor 104 through the power transformer primary, and conductor 100. The conductors 107 and 108, of course, supply the tuning indicating voltmeters 25 96 and the indicating red lights 14 and 91 at their respective locations in a multiple arrangement. The control for rotating the tuning condensers in one direction is a circuit through coil 41, over a lead to any of the buttons 11 or 93 in 30 parallel and back over a common circuit through the "off" buttons, conductor 101, conductor 100, the power supply, conductor 102, contact 116 to coil 41. The energizing circuit for coil 42 is over a lead to any of buttons 12 and 94 and back over 35 the circuit just traced for coil 41.

With this type of remote control system, the moving of a unit from one remote point to another remote point is eliminated. These various remote control units may be placed in convenient locations in the various rooms of a home, in the walls of a room or in an out of the way place where they may be reached when it is desired to adjust the tuning of the radio receiver.

The circuits shown and described above are also adaptable where the receiving unit is placed in a location remote from that of the loud speaker 38 such as the cellar or attic.

Although the invention is shown embodied in a particular type of radio receiver, and in connection with two specific remote control circuits, it is to be understood that the invention is not limited to these embodiments but only by the scope of the appended claims.

What is claimed is:

1. In combination with a radio receiving set provided with a mechanical tuning mechanism and a remote control socket, a local control unit at said receiving set, a portable remote control unit adapted to be plugged into said socket, said portable unit and said local unit each being provided with "on" and "off" buttons, a frequency indicator and a volume controller, means under control of said local control unit to transfer the control from said remote control unit to said local control unit, means under control of said remote control unit to transfer the control of said set from said local control unit to the remote control unit, and means at each control unit to indicate which of said control units is operative.

2. A radio receiver having motor operated tuning apparatus including a motor rotatably connected to the common shaft of a plurality of tuning elements, means including variable resistances for controlling the direction of rotation of said

- motor and the speed thereof, remote control means for energizing and de-energizing said radio receiver, local control means for said receiver, said local and remote control means comprising 5 relays located at said receiver, said relays being operative to change the control of said receiver from one position to another.
3. In a radio receiving system, a receiver, tuning means therefor, a motor for controlling said 10 tuning means, a first means located at the receiver and a second means located at a remote point for controlling said motor, relay means located at the receiver responsive to the operation of a switch located at the receiver and to the operation 15 of another switch located at the remote point for placing said motor under control of said first and second means, respectively, and means at each station namely at the receiver and at the remote point for transferring control of the receiver thereto from the other station and for preventing continuance of control at said other station.
4. In a radio receiving system, a receiver, tuning means and a power supply therefor, a motor 25 for controlling said tuning means, a first means located at the receiver and a second means located at a remote point, for controlling said motor, relay means located at the receiver responsive to the operation of a switch located at the receiver and to the 30 operation of another switch located at the remote point, for placing said motor under control of said first and second means, respectively, and for associating said power supply with the receiver, and means at each station namely at the receiver and at the remote point for transferring control of the receiver thereto from the other station and for preventing continuance of control at said other station.
5. In a radio receiving system, a receiver, tuning 35 means therefor, a motor for controlling said tuning means, a first means located at the receiver and a second means located at a remote point for controlling said motor, relay means located at the receiver and responsive to the operation 40 of a switch located at the receiver for placing said motor under control of said first means, said relay means being thereafter de-energizable in response to the operation of a first switch located at the remote point to remove said motor from control of said first means, and being again 45 responsive to the operation of a second switch located at the remote point to place said motor under control of said second means.
6. In a radio receiving system, a receiver, tuning 50 means therefor, a motor for controlling said tuning means, a first means located at the receiver and a second means located at a remote point for controlling said motor, relay means located at the receiver responsive to the operation 55 of a switch located at the receiver and to the operation of another switch located at the remote point for placing said motor under control of said first and second means, respectively, and means for indicating at both the receiver and the remote point when the control is at the receiver and when it is at the remote point, and a switch at each station namely at the receiver and at the remote point for restoring said relay means to unoperated condition irrespective of the point 60 from which said relay means was operated.
7. In a radio receiving system, a receiver, tuning 65 means therefor, means located at the receiver and other means located at a remote point for controlling said tuning means, and relay means located at the receiver but controlled alter- 70 nately at the receiver and from the remote point for placing the tuning means under control of the tuning control means at the receiver and at the remote point, respectively, and a switch at each station namely at the receiver and at the remote point for restoring said relay means to unoperated condition irrespective of the point from which said relay means was operated.
8. In a radio receiving system, a receiver, tuning 75 means therefor, means located at the receiver and other means located at a remote point for controlling said tuning means, relay means located at the receiver and other means located at the remote point for controlling said relay means, the relay means being effective when controlled at the receiver for placing the tuning means under control of the tuning control means at the receiver, and being thereafter effective when controlled from the remote point to transfer said tuning means to the control of the tuning control means located at the remote point and to prevent continuance of control at said receiver.
9. In a radio receiving system, a receiver, tuning means therefor, means located at the receiver and other means located at a remote point for controlling said tuning means, relay means located at the receiver, means located at the remote point for alternately controlling said relay means, said relay means being effective when controlled from the remote point to place the tuning means under control of the tuning control means at the remote point, and said relay means being effective when thereafter controlled at the receiver for transferring the control of the tuning means to the tuning control means at the receiver and to prevent continuance of control at said remote point.
10. In a radio receiving system, a receiver, tuning and volume control means located at the receiver and also at a remote point, said means being normally dis-associated from said receiver, relay means located at the receiver for associating alternately with the receiver the tuning and volume control means located at the receiver and at the remote point, and means located at the receiver and other means located at the remote point for alternately controlling the relay means, and a switch at each station namely at the receiver and at the remote point for restoring said relay means to unoperated condition irrespective of the point from which said relay means was operated.
11. In a radio receiving system, a receiver, tuning means therefor, a motor for controlling said tuning means, a first means located at the receiver and a second means located at a remote point for controlling the motor, a first relay located at the receiver for placing the motor under control of the first means, a second relay located at the receiver for placing the motor under control of the second means, and a switch located at the receiver and another located at the remote point for controlling operation of the first and second relay, respectively, and another switch at each station for controlling the restoration of the operated one of said relays to unoperated condition.
12. In a radio receiving system, a receiver, tuning means therefor, a motor for controlling said tuning means, a first means located at the receiver and a second means located at a remote point for controlling the motor, a first relay located at the receiver and effective, when oper- 75

ated, to place the motor under control of the first means, a second relay located at the receiver and effective, when operated, to place the motor under control of the second means, the first and second relays being actuated upon the operation of a first switch at the receiver and at the remote point, respectively, and a second switch at each station for controlling the release of the actuated one of said relays.

10. 13. In a radio receiving set, a radio receiver, tuning means therefor, a motor for controlling said means, control means located at each of a plurality of stations for controlling said motor, a relay located at said radio receiver controlling the operating circuit of the motor, a switch at one of said stations, an energizing circuit for the relay closed upon operation of said switch, a holding circuit for said relay established upon operation thereof, and means at each station for controlling the opening of said holding circuit.

15. 14. In a radio receiving set, a radio receiver, tuning means therefor, a motor for controlling said means, control means located at each of a plurality of stations for controlling said motor, a relay located at said radio receiver controlling

the operating circuit of the motor, a switch at one of said stations, an energizing circuit for the relay closed upon operation of said switch, a holding circuit for said relay established upon operation thereof, and a switch at each station having normally closed contacts included in said holding circuit.

20. 15. In a radio receiving set, a radio receiver, tuning means therefor, a motor for controlling said means, control means located at each of a plurality of stations for controlling said motor, a relay located at said radio receiver controlling the operating circuit of the motor, a switch at one of said stations, an energizing circuit for the relay closed upon operation of said switch, a holding circuit for said relay established upon operation thereof, means at each station for controlling the opening of said holding circuit, a second relay located at said receiver for controlling said motor, an energizing circuit for the second relay extending through all stations, and a holding circuit for said second relay having said normally closed contacts included therein.

LEWIS M. CLEMENT. 25
